 Radio Corporation of America, a corporation
 of Delaware

Application June 25, 1946, Serial No. 679,075

5 Claims. (Cl. 178—44)

1

This invention relates to radio frequency transmission lines and particularly to arrangements for transmission of radio frequency energy between different sources thereof and relatively rotatable equipment respectively associated therewith.

In accordance with the invention as applied, for example, to a system in which two antennas on a common rotatable mount are connected by coaxial type transmission lines to their respective receivers or transmitters, the two lines are effectively brought into coaxial alignment in the axis of rotation of a double rotary joint by feed-through stubs and transformer sections which provide for merger of the conductors of the incoming, or outgoing, lines into a three-conductor dual-line with complete avoidance of electrical coupling between the two lines at all wavelengths for which the walls of the conductors act as perfect shields.

The invention further resides in features of construction and arrangement hereinafter described and claimed.

For further understanding of the invention and for illustration of constructions utilized, reference is made to the accompanying drawings, in which:

Figure 1 is a cross-sectional view showing in simplified form the construction of a dual rotary joint; and associated networks necessary to bring the lines into concentricity.

Figures 1-A and 1-B are explanatory figures; Figure 2, in cross-section, shows a simplified form of another type of rotary joint; and associated networks necessary to bring the lines into concentricity.

Figure 3, partly in cross-section, shows a rotary joint construction for connecting two antennas respectively to two relatively stationary radio equipments; and

Figure 4 is a cross-sectional view showing in detail the construction of one unit of a double coaxial rotary joint.

Referring to Figure 1, it is assumed, for purposes of explanation, that the two concentric lines 1 and 2 in the lower portion of the figure extend respectively from radio equipments used, for example, for communication, object location or identification purposes, and that their continuations in the upper portion of the figure separately extend to two suitable loads, for example antennas. The radio frequency energy transmitted by line 1 comprising the concentric conductors 10 and 11 is to be kept isolated from the radio frequency energy transmitted by line

2 comprising the concentric conductors 12 and 13. In the lower portion of the figure, the two lines 1 and 2 merge into a three-conductor line 11, 12 and 13 which in the upper portion of the figure is branched out again to form two concentric lines 1 and 2. At the aforesaid physical merger of the lines, the outer conductor 10 of line 1 joins the inner conductor 13 of line 2 and serves as a continuation of it until the branch point is reached.

In the vicinity of the merger of the lines, the line 2 is provided with a transformer section T₂ whose characteristic impedance is different from that of the adjoining sections of that line; preferably, within the limits of the transformer section T₂, the diameter of the inner conductor 13 of line 2 is suitably enlarged to attain that ratio of conductor diameters which affords the different desired impedance. The length of the transformer section T₂ is an even number of quarter wavelengths at a preselected frequency, for example the mean frequency of the band or range of frequencies to be transmitted by line 2, so that the line sees the same impedance looking into section T from either end thereof.

Also in the vicinity of the merger of the lines 1 and 2, there is provided an extension 16 of the outer conductor 12 of line 2 which surrounds the terminal section 17 of the incoming line 1; the outer conductor 10 of line 1 and the section 16 of the outer conductor of line 2 form a stub S₂ of line 2 through which line 1 extends. The stub S₂ is preferably closed-ended mechanically to support the line 1 and, in such case, extends an odd number of quarter wavelengths from the merger of the lines. This feed-through stub and transformer arrangement, as well as those later described, provides for physical merger of the two transmission lines yet avoids electrical coupling between them and further adapts line 2 for transmission of radio frequency energy throughout one or more wide bands of frequency with low reflection, that is, with low standing wave ratio.

Referring to Figure 1-A, for a purely resistive load of fixed magnitude, the broad band stub support arrangement is substantially reflectionless at three frequencies, one (f_0) at the center of the band and another two on opposite sides of the center frequency and mathematically related thereto in dependence upon design of the arrangement.

The curve C, Figure 1-A, exemplifies the reflection/frequency characteristic of a stub and transformer arrangement affording a band (f_1 to

f_2) of frequencies within which energy is transmitted with low reflection. Curve E is the corresponding characteristic of a similar arrangement affording a wider band (f_1' to f_2') of frequencies within which energy is transmitted with low reflection but at some frequencies with somewhat higher reflection than for curve C. There is an infinity of such curves, each with different end points F_1'' and F_2'' .

In general, the wider the separation of the zero reflection frequencies, the greater the reflection at some frequencies within the band. The maximum band width to be used in a particular case depends upon the reflection which can be tolerated at the worst point in the band; for example, some transmitting systems exhibit instability when the reflections in the transmission line exceed certain fixed values for the systems. The stub and transformer combinations would then be designed so that their combined reflection would be less than the permissible value.

The upper limit of the band, Figure 1-A, is the frequency $2f_0$ at which the stub becomes a half-wave long and the lower limit is zero but the practical limits, considering tolerable reflection, is from about $0.65f_0$ to about $1.35f_0$.

In the simplest form of feed-through, broadbanding arrangement, the stub, such as S_2 of Figure 1, is one-quarter wavelength long at mid-band frequency and the transformer section, such as T of Figure 1, is one-half wavelength long at that frequency and is symmetrical with respect to the stub.

The closed-ended stub may be any odd number of quarter wavelengths long and the transformer section is preferably twice the stub length and centrally located. In any event, for the longer transformer sections the median line of the stub should be an odd number of quarter wavelengths from each end of the transformer section. Such arrangements limit the permissible band width but, on the other hand, as indicated by curve D of Figure 1-B, provide for two or more band-pass ranges in harmonic relationship.

A mathematical analysis of the network discloses that, if the following symbolism is designated and applied to Figure 1:

Z_0 =characteristic impedance of line 2 as well as the stub section comprised of conductors 16, and 17,

Z_1 =characteristic impedance of the transformers T_1 and T_2 ,

we find the relationship,

$$\frac{Z_1^3}{Z_0^3} + 2\frac{Z_1^2}{Z_0^2} + \frac{1}{P^2} \frac{Z_1}{Z_0} - 2 = 0 \quad (1)$$

where

$$P = \tan \frac{\pi \lambda_0}{2 \lambda} = \tan \frac{\pi f}{2 f_0}$$

and

λ_0 =wavelength at center band (f_0)

and

λ =wavelength (variable) corresponding to frequency (f).

This equation (1) governs the behavior of the stub and transformer combination. To design one, f_1 or f_2 and f_0 are selected, and P is determined. Then insert the value of P into (1) and solve the resulting cubic equation in

$$\frac{Z_1}{Z_0}$$

$$\frac{Z_1}{Z_0}$$

Knowing in advance, the value of Z_0 , there is obtained the necessary value for Z_1 . It will be found that f_1 and f_2 will be removed from f_0 by equal percentages of f_0 . The band is then investigated for reflection by other means either mathematical or experimental.

Reverting to specific discussion of Figure 1, from the stub S_2 to the upper branch point, the two lines 1 and 2 are formed by the three conductors 11, 12 and 13, the last-named serving both as the outer conductor of line 1 and the inner conductor of line 2. The elements thus far described below the line A—A are comprised in one member or unit 15 of a rotary joint construction.

The other, relatively rotatable unit 14 of the joint may be of identical construction and need not be described in detail. In brief, above the dot-dash line A—A, which may be considered a dividing plane between the two relatively rotatable parts of the joint, there are also three concentric conductors 11, 12 and 13 which are coaxially aligned with respect to the axis of rotation B—B of the joint. These three conductors, electrical continuations of the same conductors of the lower joint member 15, extend to the point at which the two lines as formed by three conductors branch out into the two separate outgoing lines having a total of four conductors.

In the vicinity of the branch point, the line 2 is provided with a transformer section T_1 similar to transformer section T_2 . It may be formed, for example, by enlargement of the diameter of conductor 13, and in cooperation with a stub section S_1 provides for low reflection of energy throughout a broad band of frequencies. The stub S_1 , similar to stub S_2 , is formed by the upper extension 16 of the outer conductor 12 of line 2 which surrounds the line 1 for a distance from the branch point which is an odd number of quarter wavelengths. In the preferred construction, the stub S_1 is a closed-ended stub having an electrical length of one-quarter wavelength. This provides the simplest construction, affords mechanical support of the section 17 of the inner line and also permits the space between the conductors of line 2 to be isolated from the ambient atmosphere and filled with suitable gas, such as carbon dioxide.

It shall be understood that the upper and lower vertically aligned sections of each of conductors 11, 12 and 13 shall be in contact to maintain their electrical continuity during relative rotation of the two units of the joint. The details of a construction providing such continuity will be discussed in description of Figure 4.

In the modification shown in Figure 1, the line 2 in effect continues straight through the rotary joint without any bends or change in direction. In some installations, it may be necessary or desirable to have bends in both lines adjacent their physical joinder or separation at the rotary joint. A construction meeting this requirement for both joint units is shown in simplified form in Figure 2. Except in particulars specifically discussed, the physical and electrical relations of the conductors of the lines to and from and within the joint are the same as above specifically discussed in connection with Figure 1.

Referring to the lower unit 23 of the joint, Figure 2, both lines 1 and 2 extend horizontally toward their merger point where they turn

upwardly through a right angle and merge into a three-conductor line concentric with the axis of rotation B of the joint. Above the dividing line A—A between the two relatively rotatable units 22, 23 of the joint, the three-conductor line continues to the branch point at which it divides into the outgoing horizontal sections of lines 1 and 2.

More specifically, at the bends where line 2 enters and leaves the rotary joint, it is provided with transformer sections T₃ and T₄, each comprised in part in the horizontal section of the line and in part in the vertical section. Preferably, each bend is midway of the associated transformer section, or if the section is more than a half wavelength, at an odd number of quarter wavelengths from the ends of the section.

The joint units are also provided with feed-through stubs S₃ and S₄, each formed by a continuation, beyond the bend, of the outer conductor 20 of the horizontal portion of the larger line 2 and the outer conductor 18 of that portion of the smaller line 1 surrounded thereby. More specifically, the lower stub S₃ is formed by the lower extension 24 of outer conductor 20 of incoming line 2 and the terminal portion 25 of the incoming line 1; the upper stub S₄ is formed by the upper extension 24 of the outer conductor 20 of outgoing line 2 and the initial portion 25 of the outgoing line 1. Preferably the stubs are short-circuited or closed-ended mechanically to support the inner line and to provide a gas-tight seal permitting the line 2 to be filled with a dry inert gas at super-atmospheric pressure.

With short-circuited stubs, their electrical length should be an odd number of quarter wavelengths. Preferably, the stubs S₃, S₄ are each one-quarter wavelength long and the transformer sections T₃ and T₄ with which they co-act are a half wavelength long. As in the type joint shown in Figure 1, the feed-through stubs and the associated transformer sections provide for physical merger of the lines without introduction of electrical coupling between them and co-act, so far as line 2 is concerned, over a wide band of frequencies so suiting the arrangement for operation with radio equipment whose signal energy, as in object-location or television, requires a wide band of frequencies, or which at different times is tuned to different frequencies of a band.

It is feasible to use a double coaxial rotary joint construction whose upper (or lower) element is of the straight-through type shown in Figure 1 and whose lower (or upper) element is of the bend type shown in Figure 2. Referring to Figure 3, for example, the lower rotary joint member 23, of type shown in Figure 2, is fastened as by mounting plate 33 interiorly of the cylindrical base member 31 of a pedestal mount 30 upon whose rotatable cap member 32 are secured two directional antenna systems, generically exemplified by 28 and 29, and respectively connected by the concentric transmission lines 1 and 2 to the radio equipments 26 and 27.

The upper member or unit 14 of the rotary joint, of type shown in Figure 1, is fastened as by a mounting plate 34 to the rotatable member 32 of the common pedestal mount 30 of the antennas. An electric motor, or other suitable device not shown, may be utilized to effect rotation of the upper part of the joint during continued transmission of radio frequency energy to or from the two antenna systems by their respective transmission lines.

Referring to Figure 4 which shows in detail

the construction of a rotary joint of the type shown in Figure 2, the body member 35, of which the mounting plate 33 may be an integral part, is in the form of a hollow T joint whose open horizontal ends are recessed to receive the tubular sections 36 and 49, the former serving as the outer conductor of a feed-through stub and the latter as the outer conductor of transmission line 2.

- 10 The closed or short-circuited end of the stub is formed by cap member 37 suitably recessed to receive the tube 36. The closure member 37 is provided with a central aperture or bore which at one end receives the outer conductor 38 of transmission line 1 and which at the other end receives and supports the tube 39 which serves as a continuation of the outer conductor of line 1 and as the inner conductor of the stub.
- 15 The other end of tube 39 is received by an open end of the inner T member 40 which, as hereinafter appears, forms the central part of a transformer section of line 2 and as a continuation of the outer conductor of line 1.

20 The inner conductor 41 of line 1, supported centrally of the outer conductor 38 by a series of insulating discs or washers 42, is provided with a terminal plug 43 received by the socket end of conductor 44, which serves as a continuation of the inner conductor of line 1. The ratio of the 25 outer diameter of conductor 44 to the inner diameter of tube 39 which surrounds it is the same as the ratio of the corresponding diameters of conductor 41 and tube 38 so that the characteristic impedance of line 1 remains unchanged: for 30 like reason, the opening in plug 37 and the end of conductor 41 are smoothly and similarly tapered.

35 The left end of conductor 44 is provided with a socket to receive the plug 46 extending from member 47a which serves as a further continuation of the inner conductor of line 1. The left end of member 47a threadably receives the lower end of the vertically extending member 47b which is in alignment with the axis of rotation B—B of the joint and serves as a further continuation of the inner conductor of line 1. The sleeve member 48 which fits over the tubular vertical extension of member 40 serves both as a continuation of the outer conductor of line 1 and, as hereinafter 40 appears, also of the inner conductor of the larger line 2.

45 The inner conductor 50 of line 2 is supported centrally of the outer conductor 49 by the spacer discs 51 of suitable insulating material and at its 50 termination is slidably received by the socket end of member 52 which serves as a continuation thereof. A bolt, as shown, may be provided to secure these two parts to each other. The other end of member 52 receives the left end of the inner T joint member 40 and with it forms part of a transformer section, as will be understood from previous discussion of Figure 2.

55 As thus far described, the construction provides for merger of the four conductors of the horizontal extensions of lines 1 and 2 into three 60 vertically extending concentric conductors in coaxial alignment with the axis of rotation of the joint; at this part of the joint, the three concentric conductors are members 47b, 48 and 35 which, as now described, are in alignment with and respectively engage three similarly concentric conductors which rotate with respect thereto about axis B—B.

65 From an upper, generally similar, feed-through stub and transformer construction there downwardly extend the three concentric conductors.

62, 63 and 55, the first-named serving as the inner conductor of line 1, the second-named serving both as the outer conductor of line 1 and as the inner conductor of line 2, and the last-named serving as the outer conductor of line 2.

The stationary member 35 of the lower joint unit engages the lower face of the relatively rotatable member 53 to the upper end of which is secured the tubular concentric member 54 which receives the lower end of the outer vertical concentric conductor 55. Consequently members 53, 54 and 55 serve as the outer conductor of that part of line 2 which is rotatable about axis B-B of the joint.

Reverting to the physically common conductor of the two lines 1 and 2, the sleeve 56 which receives the upper end of above-mentioned sleeve 48 and the lower end of sleeve 57 serves electrically to connect them during their relative rotation: preferably sleeve 56 is free to rotate about both of the other members, the areas of overlap and closeness of fit insuring low loss of radio frequency energy transferred despite use of a light lubricant on the bearing surfaces of the sleeves.

The upper end of sleeve 57 receives and is secured to the lower end of tubular member 58 which forms the last part of the transformer section beginning with member 52. The upper end of member 58 received the lower end of conductor 63 which forms the further continuation of the outer conductor of line 1 and of the inner conductor of line 2.

Beginning with member 47b, the vertical continuation of the inner conductor of line 1 includes the member 59 whose lower plug end is received by the upper socket end of member 47b, the sleeve 60 which receives the upper plug end of member 59 and the lower plug end of member 61, the member 61 whose upper plug end is received by the lower socket end of the central conductor 62. The upper plug end of member 61 is preferably rigidly connected to the lower socket end of member 62 as by silver solder and the upper socket end of member 60 is preferably rigidly connected to the lower plug end of member 61 as by a tight press fit. There is thus circumvented possibility of annealing of the spring fingers of the lower socket end of member 60 which engage and rotate with respect to the upper plug end of member 59.

As shown, the proper spacing and alignment of conductors 55, 62 and 63 are preserved by the insulating spacers 45 and 51. The relatively movable parts of each conductor of the three-conductor line overlap sufficiently to insure continuance of alignment during rotation.

The pipe connection 64 in the stationary member 35 is for introduction of inert gas into the space between the inner and outer conductors of line 2. The construction of the relatively rotatable parts 35 and 53 is such that escape of gas is minimized; however, the sealing features at that point are not specifically part of the present invention and are not disclosed.

It shall be understood the invention is not limited to the particular arrangements disclosed but includes changes and modifications within the scope of the appended claims.

I claim as my invention:

1. A dual rotary joint construction providing for transmission of radio frequency energy over a band of wavelengths between relatively rotatable portions of each of two concentric lines comprising two relatively rotatable units each including three concentric conductors coaxially aligned

with respect to the axis of rotation of the joint and connected respectively to the corresponding conductors of the other unit, each of said units comprising an arrangement for merging relatively-

5 ly fixed portions of the two concentric transmission lines with said three conductors whose intermediate conductor serves both as the inner conductor of the first of said lines and as the outer conductor of the second of said lines, the relatively rotatable portions of the first of said lines each having a transformer section whose electrical length is an even number of quarter wavelengths substantially midway of said band, and each of said units including a feed-through stub 10 for the second of said lines, the inner conductor of the stub being the outer conductor of the second line and joining the inner conductor of the transformer section of the first line at an odd number of quarter wavelengths from each end 15 of that section, and the outer conductor of the stub being an extension of the outer conductor of the first line and whose electrical length is an integral number of quarter wavelengths, said stubs and transformers thereby coacting to minimize electrical coupling between said lines throughout said band of wavelengths.

2. A dual rotary joint construction providing for transmission of radio frequency energy over a band of wavelengths between relatively rotatable portions of each of two concentric lines without introduction of electrical coupling between the lines comprising two relatively rotatable units each including three concentric conductors coaxially aligned with respect to the axis of rotation of the joint and connected respectively to the corresponding conductors of the other unit, the outermost and innermost conductors of each unit serving respectively as continuations of the outer conductor of the first of said lines and the inner conductor of the second of said lines and the intermediate conductor serving as a continuation of both the inner conductor of the first of said lines and the outer conductor of the second of said lines, said first line adjacent its joinder 20 with each unit having a transformer section whose characteristic impedance is lower than that of adjoining sections and a closed-ended extension of its outer conductor which surrounds the second line in the vicinity of its joinder with the unit and forms therewith a feed-through stub extension of the first line, said transformer sections each being an integral number of half wavelengths long, said closed-ended feed-through stubs each being an odd number of quarter wavelengths long and extending from the corresponding transformer section at an odd number of quarter wavelengths from each end thereof, so to minimize electrical coupling between said lines throughout said band of wavelengths.

3. A dual rotary joint construction providing for transmission of radio frequency energy over a band of wavelengths between relatively rotatable portions of each of two concentric lines without introduction of electrical coupling between the lines comprising two relatively rotatable units each including three concentric conductors coaxially aligned with respect to the axis of rotation of the joint and connected respectively to the corresponding conductors of the other unit, the outermost and innermost conductors of each unit serving respectively as continuations of the outer conductor of the first of said lines and the inner conductor of the second of said lines and the intermediate conductor serving as a continuation of both the inner conductor

of the first of said lines and the outer conductor of the second of said lines, said first line having adjacent its connection with each unit a transformer section whose characteristic impedance is lower than that of adjoining sections and whose electrical length is an even number of quarter wavelengths, and also having adjacent its said connection a closed-ended extension of its outer conductor which surrounds the second line for an odd number of quarter wavelengths and forms therewith a feed-through stub extension for said second line electrically coaxing with said transformer section of said first line in avoidance of electrical coupling between said lines throughout said band of wavelengths.

4. A dual rotary joint construction providing for transmission of radio frequency energy over a band of wavelengths between relatively rotatable portions of each of two concentric lines without introduction of electrical coupling between the lines comprising two relatively rotatable units each including three concentric conductors coaxially aligned with respect to the axis of rotation of the joint and connected respectively to the corresponding conductors of the other unit, the outermost and innermost conductors of each unit serving respectively as continuations of the outer conductor of the first of said lines and the inner conductor of the second of said lines and the intermediate conductor serving as a continuation of both the inner conductor of the first of said lines and the outer conductor of the second of said lines, said first line having adjacent its connection with each unit a transformer section whose characteristic impedance is lower than the that of adjoining sections and which is a half wavelength long and also having adjacent its said connection a closed-ended extension of its outer conductor which surrounds the second line for one quarter wavelength and forms therewith a feed-through stub extension for said second line and electrically coaxing with said transformer section of said first line in avoidance of electrical coupling between said lines throughout said wide band of wavelengths.

5. A coaxial line arrangement for transmission of radio frequency energy between sources thereof and relatively rotatable equipment respectively connected thereto by coaxial lines each having an inner and an outer conductor comprising two relatively rotatable rotary-joint units each including three concentric conductors at least in part coaxially aligned with the axis of rotation of the joint for connection respectively with the corresponding conductors of the other unit, the intermediate conductor serving both as the inner conductor of the first of said coaxial lines and as the outer conductor of the second of said coaxial lines, said first of said lines including 15 half-wave transformer sections, one for each unit, and closed-ended quarter-wave stubs, one for each unit, each comprising an extension of the outermost of said three concentric conductors and a section of the second of said lines which 20 extends therethrough for connection with the other two of said three concentric conductors, said stubs each mechanically supporting the associated section of the second line and extending from the center of the corresponding transformer 25 section of the first line to attain a low standing-wave ratio over a broad band of frequencies and negligible electrical coupling between said lines throughout said band of frequencies.
